UNITED STATES PATENT OFFICE.

FRANK C. WHITE, OF MERIDEN, CONNECTICUT.

MECHANICAL MUSIC-PLAYING INSTRUMENT.

SPECIFICATION forming part of Letters Patent No. 764,221, dated July 5, 1904.

Application filed December 26, 1903. Serial No. 186,524. (No model.)

To all whom it may concern:

Be it known that I, FRANK C. WHITE, a citizen of the United States, residing at Meriden, in the county of New Haven and State of Connecticut, have invented new and useful Improvements in Mechanical Music-Playing Instruments, of which the following, together with the accompanying drawings, is a specification sufficiently full, clear, and exact to enable persons skilled in the art to which this invention appertains to make and use the same.

My present invention relates to a novel construction and combination of brake mechanism for employment in connection with the music-sheet-operating rolls in pneumatically-controlled mechanical musical instruments, the object being to provide a practically efficient and simple mechanism adapted for the alternate exertion of resistance in connection with the music-sheet spool or roll and the take-up spool or draft-roller, and also means for shifting the brake for contact or action with one roller mechanism or the other coincident with the manipulation of the draft-controlling or reroll stop of the instrument, as more fully hereinafter explained.

Another object is to provide a dual-acting brake device of the character described and operative in connection with frictional surfaces carried on the axles of the draft and music-sheet rollers, means for automatically shifting the brake-contact from one to the other, and means for affording resilient or yielding contact of the braking-surfaces.

These objects I attain by mechanism the nature of which is illustrated in the accompanying drawings, wherein—

Figure 1 represents a plan view of the music-sheet-operating parts in a mechanical musical instrument embodying my invention. Fig. 2 represents, on a somewhat larger scale, a sectional elevation of the mechanism at line X-X on Fig. 1 and looking from the left-hand side. Fig. 3 is a side-view diagram illustrating a modification in the form of the mechanism. Fig. 4 is a plan view of the brake-bar as employed in Fig. 3, and Fig. 5 is a perspective diagram illustrating a modification showing a manner of operating the devices from the reroll stop or lever.

In Fig. 2 of the drawings my invention is illustrated as applied to an automatic piano-player of the class described in Letters Patent No. 592,641; but I do not desire to confine my invention to that particular style of instrument, as the improvement is applicable to other forms of mechanical musical instruments wherein a perforated music-sheet is passed over a tracker from a music-roll to a winding or draft roller, and vice versa.

Referring to the drawings, the part marked A represents the frame or casing, of any suitable construction.

B and B' indicate the clutch and supporting-bearing for carrying the removable music roll or spool C, upon which the perforated music-sheet M is mounted in well-known manner.

D indicates the operated draft-roller or take-up spool at the back of the tracker E, by which the music-sheet is drawn from the roll C across the face of the tracker. Said roller is journaled in the frame in well-known manner and is operated from the motor-driven shaft F by gear G' and pinion G, while H indicates the usual band or sprocket-chain connection for operating the music-roll clutch B when rerolling the music-sheet upon its spool or roll C.

The parts of a music-playing action comprising fingers or striker-levers P for playing the keys of a piano or keyboard, the puppet J or device for moving said striker-lever, actuating-lever I, operating-pneumatic K for imparting movement to operate the striker-levers, and an exhaust-chamber or wind-chest W for the pneumatics may be of usual, well-known, or any preferred construction. Such parts are not features of my present invention, but are illustrated in order to give a better understanding of the combination and operation in connection therewith of the invention herein claimed.

According to my present invention there is provided, in combination with the take-up spool or draft-roller axle, a drag-wheel or device 2, having a friction-surface, and on the music-roll-clutch axle a drag-wheel or device 3, having a friction-surface, and combined therewith I provide a brake bar or lever 5,

centrally fulcrumed at 4 upon a suitable support and provided on its arms with contact-surfaces or brake-shoes 6 and 7, preferably of hard wood, that are respectively adapted for frictional engagement with the faces of the drag-wheels 2 and 3. The contacts are made alternate—that is, either one of the brake-shoes being brought into contact with its drag-wheel while the other is moved away from its 10 drag-wheel by the tilting of the brake bar or lever 5 upon its fulcrum-pivot 4. A spring 9 is combined with the brake-lever 5 for normally swinging its rear end toward the drag-wheel 2. Said spring 9, as shown, consists of a contractile coil with its ends respectively attached to the arm of a lever 5 and to a stationary point 10 on the frame. The brake-lever is also joined by a connecting-link 12 with the movable member of a pneumatic 13, having a 20 passage 14 from its interior into the exhaust-chamber N or some portion of the instrument from which air is exhausted. Said connection 12 may in some instances be a straight rod, but is preferably made as a spring or 25 yieldable connection, as in Fig. 2, and is best provided with an adjusting button or nut 15, screw-threaded upon the end thereof.

The tiltable brake bar or lever 5 may be disposed in any convenient position in relation 30 to the drag-wheels for acting against the surfaces thereof alternately by the tilting movement of the brake-bar. In Figs. 3 and 5 it is shown as disposed below the roller-axes and drag-wheels.

35 In some instances the brake bar or lever 5 can be made with a resilient or spring portion 55, of metal or other suitable material, as in Figs. 3, 4, and 5, to afford a yieldable contact of the brake-surfaces. A valve 16 can be employed for shutting off the passage into the pneumatic 13, with a suitable connection or means 17 for working such valve, although such valve is not required in instruments wherein the wind-chamber N is shut off from the bellows-reservoir when the reroll-stop is 45 operated.

The operation is as follows: When a roll of music is to be played, the partial vacuum created within the wind-chest W for operating 50 the pneumatics K of the playing-action exhausts the pneumatic 13 through its passage 14, and its movable member or top is drawn downward, together with the connection 12, which moves the brake-lever 5 in a manner 55 to bring the pad or brake-shoe 7 into contact with the drag-wheel 3 on the music-roll clutch B and to simultaneously move the pad or brake-shoe 6 out of contact with the drag-wheel 2, which is mounted on the axle or 60 shaft of the draft-roller D, thus releasing the draft-roller and applying a resistant friction in connection with the music-roll. The force of the brake-contact is governed by the power of the pneumatic 13 and the resilient strength 65 of the spring connection. The degree of the

brake tension can be regulated by the button or nut 15 on the connecting member 12. When the mechanism for the rerolling of the music-sheet is thrown into action, the passage leading from the wind-chest W to the bellows (not shown) is closed in well-known manner by the manipulation of the reroll-stop, thereby relieving the exhaust in the wind-chest and permitting the pneumatic 13 to expand by the action of the spring 9 moving the brake-lever in a manner to bring the pad or shoe 6 into contact with the drag-wheel 2 of the draft-roller D and at the same time withdraw the pad or shoe 7 from contact with the drag-wheel 3 of the music-roll clutch, thus effecting automatically the shifting of the brake-action as the change in direction of movement of the music-sheet is effected by manipulation of the "play" and "reroll" stop mechanism. 85

The diagram Fig. 5 illustrates a construction and manner of operating the brake mechanism manually and direct from the reroll stop-lever 19 instead of by a pneumatic 13. It consists of a rocker or crank wire 20, having an arm 21, that embraces the connection 12, and a crank-arm connected by link 22 with the lever 19. The extension of the link at 23 is in practice connected in well-known or suitable manner for working the valve that controls the exhaust-passage from the wind-chest to the bellows-reservoir (not shown) for letting on or cutting off the exhaust or pressure by a movement of the lever 19 from reroll to play position, or vice versa. 90 When the lever is moved to play position, the arm 21 of the rocker is swung down against the lug or button 25 and tilts the brake-bar so as to relieve the brake from draft-roller wheel 2 and apply the brake to drag-wheel 3 of the music-roll clutch. The mechanism of Fig. 5 can be used in connection with a pneumatic-actuator, the pneumatic being combined with the connection 12, substantially in the same manner as shown in 95 Figs. 2 and 3.

Brake mechanism of different character having been employed prior to my invention in combination with a music-sheet roll for affording frictional resistance to cause the 100 sheet to run taut, I do not claim the idea broadly of employing frictional resistance for the purpose named; but my invention relates to means embodying the essential characteristics set forth and defined. 105

Inasmuch as changes may be made in the construction of the mechanism by those skilled in the art without departing from the scope of my invention as defined in the claims, I do not wish to be limited to the special form of 110 embodiment herein shown and described.

What I claim, and desire to secure by Letters Patent, is—

1. In a mechanical musical instrument, the combination with the draft-roller, and the 115

- music-roll clutch, each provided with means for receiving brake-contact, of a tilting brake-bar provided with front and rear brake-surfaces that can alternately engage therewith
- 5 for resistance to the music-roll and draft-roller mechanism, and means for tilting said brake-bar to bring either of the brake members into braking contact, for the purpose set forth.
- 10 2. In a mechanical musical instrument, in combination with the draft-roller axle, and music-roll clutch or axle, each provided with means for a brake-contact, a compound brake device provided with brake-shoes that act 15 against the respective brake contact-surfaces, alternately, and means for moving said brake device to bring either of said brake-shoes into braking contact automatically, when the direction of movement of the music-sheet is 20 changed.
- 15 3. A mechanical music-playing instrument, having an exhaust-chamber, in combination, with the music winding or draft roller, a drag-wheel fixed on the axle thereof, the 25 music-roll clutch, a drag-wheel thereon, a pivotally-supported brake-bar, its respective arms provided with brake-surfaces adapted for frictional contact with said drag-wheels, an exhaust-chamber within the instrument, a 30 pneumatic having a passage communicating with said exhaust-chamber, a suitable connection joining the movable part of said pneumatic to said brake-bar, and a spring connected with said brake-bar and acting in opposition 35 to said pneumatic.
- 40 4. In a mechanical music-playing instrument in combination with mechanism for advancing and for rerolling the music-sheet, a brake mechanism comprising a single brake-lever provided with two brake shoes or surfaces adapted to act alternately for resistance to the music draft and rerolling movements, and an operating means for tilting said brake-lever to bring either brake-shoe into braking 45 contact.
- 45 5. In a mechanical music-playing instrument, in combination with the music-draft roller, the tracker and music-roll clutch; a dual brake comprising a rocking member with 50 means for alternate application to control the draft-roller and the music-roll, and a brake-actuating means for automatically shifting the brake-contact controlled by the reroll-stop.
- 55 6. In a mechanical music-playing instru-
- ment, the combination with the music-roll clutch, having a drag-wheel thereon; the music-draft roller, its axle provided with a drag-wheel or brake-receiving surface; a tiltably-supported brake-bar having contact means for 60 frictional engagement with the respective drag-wheel surfaces; means for effecting a yielding pressure for said brake-bar, and means for moving the brake-bar to bring either end thereof into braking position upon the 65 corresponding drag-wheels.
7. In a mechanical music-playing instrument, in combination with the exhaust wind-chest, the music-draft roller, its axle provided with a drag-wheel or brake contact-surface, 70 the music-roll, its clutch provided with a drag-wheel or brake contact-surface, a pivoted brake-bar provided with brake-shoes to match the respective drag-wheels, a spring for retracting said brake-bar, a pneumatic in communication with the exhaust-chamber of the instrument, a connection joining the movable member of said pneumatic to said brake-bar. 75
8. The combination with the draft-roller and music-roll clutch, each provided with a 80 drag-wheel surface, a centrally-pivoted brake-lever with arms extending to the respective drag-wheels and provided with means for frictional contact therewith, means for affording a yielding pressure of said lever, a lever-actuating pneumatic, a connecting-link from the pneumatic to the brake-lever, a regulating device for said connecting-link, a retracting-spring, and means for controlling the exhaust or pressure in said pneumatic. 85
9. In a mechanical music-playing instrument, in combination, a pneumatic finger-playing action, a wind-chest therefor, a controlling perforated music-sheet, a draft-roll and a music-roll clutch, each provided with a 90 drag-wheel or brake-receiving surface, a movable brake having brake-shoes for contacting with the respective brake-receiving surfaces, means for affording yielding action to the brake, and a pneumatic connected with said 95 brake, and having a passage into said wind-chest, for automatically shifting the brake-contact in coincidence with the reroll-stop. 100

Witness my hand this 23d day of December, 1903.
